UNITED STATES PATENT OFFICE.

CLARENCE V. ROBERTS, OF PHILADELPHIA, PENNSYLVANIA, ASSIGNOR TO ROBERTS & MANDER STOVE COMPANY, OF PHILADELPHIA, PENNSYLVANIA, A CORPORATION OF PENNSYLVANIA.

OVEN-BURNER FOR GAS-RANGES.

1,328,589.

Specification of Letters Patent. Patented Jan. 20, 1920.

Application filed October 20, 1917. Serial No. 197,569.

To all whom it may concern:

Be it known that I, CLARENCE V. ROBERTS, a citizen of the United States, residing in Philadelphia, Pennsylvania, have invented 5 certain Improvements in Oven-Burners for Gas-Ranges, of which the following is a specification.

My invention relates to certain improvements in burners located in the ovens of 10 gas ranges.

One object of my invention is to make the burner in two parts, each having an igniting extension, the two extensions being located side by side so that when one is 15 ignited the other can be ignited by simply turning on a gas cock.

A further object of the invention is to make this combined burner in a single casting.

20 In the accompanying drawings:

Figure 1 is a plan view of a portion of a gas range illustrating my improved burner;

Fig. 2 is a detached sectional plan view of the burner;

25 Fig. 3 is a sectional view on the line 3—3, Fig. 2;

Fig. 4 is a sectional view on the line 4—4,

Fig. 2;

Fig. 5 is a sectional view on the line 5—5,

30 Fig. 2;

Fig. 6 is a sectional view on the line 6—6,

Fig. 2, and

Fig. 7 is a view of a modification.

Referring to the drawings, 1 is the oven 35 of an ordinary gas range. 2 is the door, which can be hung in any suitable manner. I have shown the oven by dotted lines so as to illustrate the position of the burner in the oven. 3 is the burner made in a single 40 casting and having two sections 4 and 5 separated by partitions 6 and 7. One section has a nipple 8 which is connected to a pipe 9 and the other section has a nipple 8^a which is connected to a pipe 10. 11 is a 45 gas supply pipe and 12 is a gas cock through which gas is admitted to supply the pipe 9.

At the end of the burner 3 opposite the 50 gas supply pipe is an extension 14 leading to the front of the oven, in the present instance. The partition 7 of the burner is

carried through the length of this extension, so as to make two igniting chambers 15 and 16, as clearly shown in Figs. 2 and 3. In the walls of each of these chambers are perforations 17, and in the longitudinal 55 burners 4^a and 5^a of the burner 3 are two sets of perforations 18, as shown in Fig. 4, and in the transverse portions 4^b and 4^c are perforations 19, Figs. 5 and 6, but it will be understood that the perforations in the 60 burner may be varied, as desired, depending considerably upon the construction of the gas range and its oven, and also on the relative position of the two longitudinal portions 4^a and 5^a.

65 It will be noticed that the igniting extensions of the burner are arranged side by side so that when both gas cocks are turned on a single match will simultaneously ignite the gas escaping from both burners, but, if 70 it be desired to use only one section of the burner then one gas cock is turned and the match is applied at the same point, but only the gas escaping from one-half of the burner will be ignited.

75 If it be desired to use the other half of the burner at any time during the baking to increase the heat, all that is necessary is to turn on the other gas cock and the gas escaping from the igniting extension of the 80 burner will be ignited by the burning gas at the other extension so that a second application of a match is unnecessary.

85 In some instances, a triple burner may be used by increasing the sections and providing a third partition, as shown in Fig. 7, 7^a being one partition between the section 5^b and a central section 5^d, and 7^b being a partition separating the section 5^d from the section 4^a and the openings in the igniting 90 extensions are such that the flame from the two side chambers would be directed toward the center so that any one of the burners could be first ignited and either one, or both, of the other two burners could be ignited 95 from the first burner.

I claim:

The combination in a gas range, of an oven; a gas burner made in a single casting and having two longitudinal sections per-

forated for the escape of gas and two end sections, also perforated; a partition in one of the end sections; an igniting portion forming a continuation of the other end section and having a partition therein, said igniting portion also being perforated, the parts being so arranged that the gas escap-

ing from one, or both, of the burners, can be ignited, or the gas escaping from one burner can be ignited from the flame of the other burner.

In witness whereof I affix my signature.

CLARENCE V. ROBERTS.
